METHOD OF MAKING RECESSED HEAD SCREWS

Joseph J. Tomalis, Providence, R. I., assignor to
American Screw Company, Providence, R. I.,
a corporation of Rhode Island

Original application January 14, 1938, Serial No.
185,036. Divided and this application June 10,
1938, Serial No. 213,013

2 Claims. (Cl. 10—10)

This invention relates to screw manufacture and more particularly to a method of manufacturing headed blanks for screws. While the invention is not so limited, it is primarily intended for the manufacture of blanks for screws which have a recessed head such as disclosed in U. S. Patent No. 2,046,839. This application is a division of my copending application Serial No. 185,036, filed January 14, 1938.

It is a general object of the invention to provide a novel and improved method of heading and recessing screw blanks formed from suitable wire.

More particularly it is an object of the invention to provide a method for making screws of the kind mentioned by first forming a screw blank having a head provided with a plurality of radial enlargements thereon and then punching a recess with radial grooves in the head, the 20 grooves being punched in said radial enlargements of the blank.

By first forming a head with radial enlargements on the blank and then punching the recess so that the wings on the punch penetrate such 25 enlargements, it has been found that the operation of making screws of this kind is greatly improved and simplified. Heretofore it has been generally considered necessary to subject the screw blanks to a shaving operation after the 30 recess is punched in the head. This was done to remove excess metal and produce a smooth surface on the head which would be free from fins or projections. The present method obviates the necessity of such shaving operation 35 on the surface of the screw heads and also eliminates any danger of shaving away the rounded corners at the intersections of the recess with the surface of the head as described and claimed in U. S. Patent No. 2,084,079.

In carrying out the present method any suitable mechanism may be used for operating and controlling the punches, but I preferably employ the mechanism illustrated in the accompanying drawings, which mechanism is claimed in my 45 said copending application and which is herein described as one means of carrying out the method of this application.

In said drawings:

Figure 1 is a longitudinal vertical section 50 through the movable punch assembly and its fastenings showing also the stationary die. In this figure the upsetting operation of the first punch is shown partially completed;

Figure 2 is a transverse vertical sectional view 55 of the punch assembly taken on the broken line

2—2 of Figure 1, the ends of the punches being shown in elevation;

Figure 3 is a vertical section similar to Figure 1 showing the blank being carried into the stationary die by the first punch;

Figure 4 is a plan view partly in section of the die and punch portions of a screw heading machine with the moving parts and wire blank in the same position as in Figure 3;

Figure 5 is a horizontal section of the same 10 parts showing the completion of the first punch upsetting operation;

Figures 6 and 6A are respectively an enlarged end elevation and a partial longitudinal section of the first punch;

Figure 6B illustrates the shape of a blank after the first punch has operated thereon; and

Figure 7 is an enlarged end elevation of the second punch.

As customary in cold-heading machines for 20 making screw blanks, the present arrangement includes a stationary part or anvil section 10 which opposes a reciprocating gate or cross-head 11 adapted to move toward and from as well as laterally of the stationary anvil 10. Mounted 25 in the stationary part 10 is a fixed die member 12 having a longitudinal aperture therethrough to closely fit the wire from which the screw shank or body is formed and through which a knock-out pin 13 operates. Another fixed die 30 member 14 is also mounted in the stationary part 10 and through this die the wire W is intermittently fed by any well-known mechanism. The length of the blank to be used is determined by the wire stop S against which the end of the wire comes in contact to complete the feed 35 through the die 14. The cutting and carrying member 15 cooperates with the die 14 to cut off a desired length of wire for a screw blank and carry it into position to be operated upon.

A punch holder 16 and a punch slide 17 are rigidly secured together as by bolts 17a and are carried by the cross-head 11. The holder 16 is thus arranged for reciprocating motion in two paths at right angles to each other. The first 45 motion is parallel to the axis of the wire blank held in the die 12 and results from the movement of the cross-head 11 in rectilinear guides (not shown) under the action of any suitable and well-known mechanism. The second path 50 of motion is vertical to present successively the first punch 18 and the second punch 19 to a blank held in the die 12 and this motion results from the punch slide 17 moving in a suitable dovetail groove in the gate or cross-head 11 as 55

indicated in the drawings and as common in the art. Each of said punches acts on the blank under the action of the first motion.

The present invention is concerned with the 5 method of forming screw blanks by two strokes of the gate or cross-head 11, the first punch 18 being adapted to carry out the operation of forming the head and enlargements on the blank and the second punch 19 being arranged to 10 form the recess in the head thus produced.

The position of the punch holder 16 with relation to the cross-head 11 and the stationary die 12 is adjustable transversely by adjusting screws 20 engaging bolts 17a and vertically by 15 adjusting studs and nuts 21 engaging the cross-head 11. The punch holder 16 may be positioned in this manner so that the hole in the first punch 18 and the nub on the second or finish punch 19 are properly aligned on the common 20 axis of the screw blank indicated at 22 and the hole in the stationary die 19 at such time as each of the above punches is vertically moved into position to oppose the blank in the die.

The first punch 18 is mounted in a socket in 25 the holder 16 and this punch is made up of three portions or sections of different diameters. The outer portion thereof closely fits and slides in a sleeve 23 secured in the socket of the holder 16 by a retaining pin 24. The intermediate portion of the punch 18 is larger in diameter than 30 the other sections and such intermediate section closely fits and slides in a bushing 25 tightly fitted in the socket of the holder. The inner smaller portion of the punch 18 is surrounded by 35 a spring 26 which bears at its rear end against the bottom of the socket in the holder and at its front end against the shoulder on the punch 18 formed by the enlarged intermediate portion thereof. Such enlarged intermediate portion of 40 the punch and the sleeve 23 provide means for preventing the spring 26 from forcing the punch too far out of the holder 16. The punch 18 from its forward end to the shoulder thereon is machined flat on one side as indicated at 18A in 45 Figs. 2 and 6, which forms a keyway through which extends a key or pin 27 vertically located in a hole in the sleeve 23. This pin prevents rotary motion of the punch 18 at all times.

The punch 18 is apertured longitudinally, the 50 outer or front end of this aperture being the same size as the aperture in the stationary die 12 and adapted to receive one end of the wire blank 22. The inner or rear portion of said aperture is somewhat enlarged. A pin 28, which 55 in effect forms part of the punch 18, is mounted in said aperture and the rear end thereof rests against or may be secured to a plug 29 tightly fitted in the holder 16, this plug being adapted to receive the shock and wear of the pin 28, and the 60 same may be replaced after being knocked out by blows through a removal hole at the rear thereof. Lubrication may be provided through the oil hole 30 to the various parts of the punch mechanism.

65 As will be seen particularly from Figs. 6 and 6A, the forward face or end of the punch 18 is provided with a central recess arranged around the aperture therein. This recess is made up of a central part 18B and four spaced radial parts or 70 depressions 18C which extend radially outwardly from said central part 18B and forwardly to the front face of the punch outside the central depression 18B. As will be seen, the parts 18B and 18C of the recess are all arranged within the 75 confines of the end of the punch. The use of a

recess of this kind on the end of the punch including the radial depressions has been found to greatly facilitate the production of recessed screw heads without subsequent expensive operations to finish the head. The recess and radial 5 depressions in the end of the punch result in the formation of a partially finished head as shown in Fig. 6B, which has substantially the shape of the depression in the end of the punch and which includes four raised portions or lobes 10 B' produced on the top of the partially completed head by the radial depressions 18C on the punch. Said lobes or enlargements are shown somewhat exaggerated on the drawings to make the disclosure more clear. The function of these 15 lobes or raised portions is important as will presently appear.

The second punch 19 is preferably movably mounted in a plug or adaptor 31 by a pin 32 after the manner disclosed in applicant's prior 20 Patent No. 2,082,085 and the adaptor is rigidly secured in a socket in the punch holder 16, being held against rotation by the cross pin 33. The punch 19 is shaped to form in the head of the blank a recess of the shape shown in said Patent 25 No. 2,046,839. To effect this result the punch is formed on the end thereof with a nub or projection having four radially arranged wings 19A surrounded by a depression 19B which produce the desired shape of recess.

30 As will be seen from the drawings the wings 19A are spaced and positioned to correspond with the radial depressions 18C in the first punch 18, that is each wing 19A extends radially in the same direction as the corresponding depression 35 18C. As the result of such arrangement, when the punch 19 is forced against the partially formed head on the blank 22, the wings 19A of the punch will engage and penetrate the enlarged portions or lobes B' on the head resulting from the de- 40 pressions 18C. These lobes or enlargements B' provide additional metal at the required points so that when the wings 19A penetrate such enlargements and the metal is forced outwardly and laterally of the wings, sufficient metal is 45 present at the proper points with the result that the completed head is smooth and perfectly circular and any subsequent shaving operation thereon is avoided. The end of the punch 19, including the wings 19A, is of such size that the 50 recess formed thereby will be positioned entirely within the confines of the head formed on the blank by the first punch.

55 Referring further to the operation of the device, a length of wire sufficient to form the screw blank 55 22 is cut off and carried into position in line with the holes in the die 12 and punch 18. The punch 18 is moved forward and one end of the blank enters the aperture in the punch 18, the other end being in line with the corresponding 60 aperture in the stationary punch 12. The cutter and carrying member 15 recedes and the forward motion of the punch assembly continues as the punch 18 encloses an increasingly larger portion of the blank until the punch pin 28 contacts the 65 end of the blank and causes the blank to move partially into the die 12 as shown particularly in Figs. 3 and 4. The blank being thus supported at both ends the cutter and carrier 15 is caused to recede, as before noted, so as to permit the punch 70 to further approach toward the die 12. The blank, actuated by the punch pin 28, travels into the die 12 until stopped by contact with the knockout pin 13, which is adjustable for different 75 lengths of screws and which allows the blank to 75

enter the die 12 a distance equal to the length of the screw desired. At that time the end of the punch 18 contacts the face of the die 12 and the punch now becomes a stationary part of the 5 punch mechanism. Further forward motion of the punch holder 16 causes the spring 26 to be compressed and while being compressed, it prevents rebound of the punch 18 away from the die 12 until such time as the resistance of the 10 metal being upset becomes greater than the spring pressure, as later explained. When the punch 18 becomes stationary against the die 12 as stated, the blank 22 has come to rest against the knockout pin 13 and further forward motion 15 of the punch assembly causes compression of the spring 26 and upsetting operation of the blank 22 begins by contact of the punch pin 28 against the same. The blank is completely enclosed by the holes in the punch 18 and die 12 so that the 20 material of the blank can and does flow only out into the recess and depressions formed in the punch face (and also into the depression formed in the die, in cases where screws with upset shoulders or countersunk heads are to be produced).

The spring 26 is so designed and constructed that as the punch pin 28 advances and at a point shortly preceding the completion of the forward stroke and upsetting operation, the rearward 30 pressure exerted on the punch 18 by the metal being upset will momentarily become greater than the forward pressure of the spring 26 upon the punch 18, with the result that the punch is caused to yield or move back a very short distance and 35 this slight rearward motion permits the metal to flow or move out laterally in all directions which ensures that all parts of the recess and depressions in the front face of the punch will be supplied with metal and then as the gate or 40 cross-head continues its forward motion the punch 18, having come in contact with the block 11, the punch becomes a rigid part of the punch assembly, and the punch is forced toward the die to complete the formation of the partially 45 formed head, having thereon the lobes or enlargements B' as before described. After the first punch recedes the second punch 18 is raised

and forced against the blank in the die to complete shaping of the head and to form the recess therein as before noted. When the gate again moves back, the knock-out pin 13 is caused by suitable mechanism to eject the finished blank 5 from the die 12.

It will thus be seen that the foregoing mechanism operates to carry out the method of this invention by first forming a head on a blank and simultaneously forming radial enlargements 10 on the head and then forming a recess in the head by forcing into the same a punch provided with radial wings so that the wings thereof engage the radial enlargements previously formed on the head.

Having thus described the invention, what is claimed as new and desired to be secured by Letters Patent is:

1. A method of making screw blanks of the type having a head provided with a recess therein having a central portion and four grooves extending radially therefrom, which method comprises subjecting the blank to the action of a first punch to form a partially completed head on the blank with four lobes or enlargements extending radially on the top of the head, and then subjecting the blank to the action of a second punch having a central portion and four radial wings extending therefrom and forcing said wings of the second punch into said 30 lobes or enlargements on the partially formed head to form the recess therein.

2. A method of making screw blanks of the type having a head provided with a recess therein having a central portion and a plurality of 35 grooves extending radially therefrom, which method comprises forming a partially completed head on the blank with a plurality of lobes or enlargements extending radially on the top thereof, and then subjecting the blank to the action of a punch having a central portion and a plurality of radial wings arranged to correspond with said lobes on the blank and forcing said wings of the punch into said lobes on the partially completed head to form the recess therein.

JOSEPH J. TOMALIS.
